CLAIM

The ornamental design for squeeze bottle caddy, as shown and described.

DESCRIPTION

FIG. 1 is a top plan view of the squeeze bottle caddy showing our new design;

FIG. 2 is a bottom plan view thereof;

FIG. 3 is a fragmentary sectional side view thereof the opposite side being identical;

FIG. 4 is a front elevational view thereof, the opposite being identical;

FIG. 5 is a bottom plan view of an alternate embodiment of FIG. 1;

FIG. 6 is a fragmentary sectional side view of FIG. 5, the opposite side being identical; and,

FIG. 7 is a front elevational view of FIG. 5, the opposite side being identical.

The undisclosed top view of the alternate embodiment is the same as the first embodiment.

FIG. 1

FIG. 2

FIG. 5

FIG. 3

FIG. 6

FIG. 4

FIG. 7
